United States Patent Office.

ERA ROSE, OF VERNON, INDIANA.

Letters Patent No. 96,482, dated November 2, 1869.

IMPROVEMENT IN DEVICE FOR REMOVING DUST FROM THRESHING-MACHINES.

The Schedule referred to in these Letters Patent and making part of the same.

To all whom it may concern:

Be it known that I, ERA ROSE, of Vernon, in the county of Jennings, and State of Indiana, have invented a new and useful Improvement in Removing Dust from Threshing-Machines; and I do hereby declare that the following is a full, clear, and exact description of the construction and operation of the same, reference being had to the accompanying drawings, making a part of this specification, in which my invention is represented by a longitudinal vertical section.

The object of this invention is to provide for use, in connection with threshing-machines, a simple, cheap, and convenient apparatus, which can be employed to take up and remove the dust from the threshing-apparatus, delivering it outside of the building in which the machine is used, or in any other convenient place.

In the drawings—

A represents the frame of the machine;

B, the pipe, which takes up the dust from the threshing-cylinder, and delivers it to the fan;

C, a larger discharge-pipe, which conducts the dust away from the fan, and delivers it at any convenient point;

D, a partial-discharge pipe, provided with a perforated screen, *d*, and a damper-valve, *d'*;

E, the fan-box; and

F, a rotary fan, operated by a belt and pulley from the power that drives the machine.

The fan-box E is in the form of a short cylinder, placed transversely with relation to the conducting-pipe, and having the fan arranged within it, as shown in the drawing.

The pipe C leads directly from the lower edge of the box, so that the wings of the fan, revolving "with the sun," will force a strong current of air directly into it from the fan-box.

The end of the pipe B does not enter at the edge, but at the end of the fan-box, as shown at *o*, and the nearer it enters to the shaft of the fan, the better will be the draught of air through the pipe, and the more effectively will the fan force out, into pipe C, any straws, sticks, &c., that may chance to come over.

A pipe or hose, of cloth, India rubber, or other suitable material, may be attached to the delivery-end of pipe C, (as shown in red,) for the purpose of conducting away the dust to any convenient point.

Having thus described my invention,

What I claim as new, and desire to secure by Letters Patent, is—

The attachment to threshing-machines herein described, when constructed and operating as set forth, that is to say, having the small pipe B *b* *b'*, the large pipe C, the fan E, and the partial-discharge pipe D, with damper *d* and screen *d'*, all arranged and operating in connection with each other, as and for the purposes specified.

To the above specification of my improvement, I have set my hand, this 10th day of April, 1869.

ERA ROSE.
